UNITED STATES PATENT OFFICE.

HENRY P. MAIDEN, OF ORD, NEBRASKA, ASSIGNOR OF ONE-THIRD TO
ROBERT C. NICHOLS, OF SAME PLACE.

CAR-COUPING.

SPECIFICATION forming part of Letters Patent No. 425,181, dated April 8, 1890.

Application filed January 18, 1890. Serial No. 337,394. (No model.)

To all whom it may concern:

Be it known that I, HENRY P. MAIDEN, residing at Ord, in the county of Valley and State of Nebraska, have invented certain new 5 and useful Improvements in Car-Couplings, of which the following is a specification.

My invention relates to car-couplings; and it has for its object to provide simple, cheap, and effective coupling devices which may be 10 readily operated for coupling or uncoupling either from the top or the sides of the car.

To this end my invention consists in sundry novel arrangements and peculiar combinations of parts, all of which will hereinafter 15 be fully described in the annexed specification and particularly pointed out in the claims, reference being had to the accompanying drawings, in which—

Figure 1 is a perspective view of my im- 20 proved coupler and the operating-levers as applied to a box-car. Fig. 2 is a horizontal section of the draw-head. Fig. 3 is a vertical longitudinal section of the same. Figs. 4 and 5 are detail views hereinafter referred to.

In the accompanying drawings the car A is 25 provided with a draw-head B of the usual form, which is provided with an internal chamber b, the side walls of which are formed with shoulders b' b' adjacent the central opening b², the upper and lower walls of said chamber and opening, however, being flush. The opening b² communicates with the usual link-receiving opening or mouth C, the sides of which slope toward said opening, as shown.

D denotes the automatic link - support, 35 formed with a projecting portion or finger d, which operates in the opening b² and normally projects beyond the vertical pin-openings e e, being held in such position by the spring E, 40 its forward movement being limited by means of the lateral wings d' d', formed on the inner end of the support, which abut the shoulders b' b', as most clearly shown in Fig. 2 of the drawings.

By constructing the draw-head so as to have 45 only the horizontally-disposed shoulders b² and making the upper and lower walls flush with the chamber b, I am enabled to provide a link-receiving opening wherein the link is 50 guided so as to engage the front walls of the

shoulders b' b', thereby relieving the spring E from too great a pressure when the cars are being coupled together. By this arrangement it will be seen that when one end of the link is in position in the draw-head the support 55 will bear against the same and cause it to assume an approximately horizontal position ready for coupling with the adjacent draw-head, thereby avoiding the necessity of the brakeman going between the cars or the employment of link-lifters.

F denotes the coupling-pin, which is of the ordinary construction, except that I form the head f with a transverse opening f', for a purpose presently explained. The pin-lifting devices, which are most clearly shown in Figs. 1, 3, and 4, consist of a vertically-disposed lifting rod or bar G, the lower end of which is formed into a lateral extension g, which is formed with a shoulder g' and a stem g², 65 which fits through the opening f' in the pin F, and is held by means of the washer g³ and pin g⁴, fitted in a manner clearly understood by reference to Fig. 4 of the drawings.

The upper end of the rod G passes through 75 a guide H, formed of a bracket - plate provided with a slotted end h, the fingers h' h' of which are turned upon themselves to form apertured ears, through which is passed a pin h², which serves to hold and guide the upper 80 end of the rod G in the slotted end of the bracket H.

The upper end of the bar G is provided with a bent portion G', forming a handle, and G² and G³ denote lateral lugs disposed one 85 above and the other below the bracket H, said lugs serving to limit the up or down movement of the bar G, said lugs engaging the bracket H in such movements.

As an additional means for lifting the pin, 90 I provide a rock-shaft I, journaled in brackets i i to the front of the car a short distance above the draw-head beam x, said shaft being formed of a single piece of rod-iron bent in the center to form a depending arm I', which 95 projects under the extension g of the bar G, the outer ends of said shaft I being bent to form handles i² i², their extreme ends being bent inward, as at i³ i³, to normally hold said handle portions from the end of the car, and 100

thereby afford a convenient means for quickly grasping the same.

- 5 L denotes a vertically - disposed pivoted rocking lever, the lower end of which is bifurcated at l' and projects over the shaft I between collars M M, adjustably secured thereon, the upper end of said bar being extended above the car and formed into a suitable handle, as shown, said upper portion being 10 also formed with a lateral bifurcated portion L', the ends l'' of which normally embrace the bar G, the projection G³ operating between said ends l'' on its vertical movement. By 15 this construction it will be seen that when it is desired to keep the coupling-pin lifted, so as not to couple during shifting of cars, (in case the brakeman be on top of the car,) by moving the lever in the direction shown by arrow 4 in Fig. 1, the bifurcated portion L' 20 will be moved under the projection G³ and hold the bar G in elevated position. The same operation of the lever L may be accomplished by means of the shaft I, in case the brakeman operates the devices from the sides 25 of the car, by pressing the said shaft I in the direction of the arrow 5, thereby forcing the upper end of the lever L into the position before described. To hold said bar I from any lateral movement which might be caused by 30 means of the jar or vibration of the car during its movement along the road, I provide a clamp - bearing O, formed of a spring-plate bent as shown, in which fits a collar P, adjustably secured on the rod I, the frictional 35 contact of said bearing-plate and the collar serving to hold said shaft from the lateral movement described.

In practice I provide a suitable shield R, which is fitted over the upper ends of the bar 40 G and the lever L, said shield serving to protect said parts from the ice and snow.

From the foregoing description, taken in connection with the drawings, the advantages and operation of my improved coupler 45 will be readily understood. It will be seen that the same is exceedingly simple in construction and can be produced at a slight cost. It can be fitted to almost any modern form of draw-head and cars, the peculiar arrangement of the bar G admitting of said devices being used on freight-cars provided with the end openings for the passage of articles of freight.

Having thus described my invention, what I 55 claim, and desire to secure by Letters Patent, is—

1. A car-coupling consisting of a draw-head formed with an internal chamber b, having shoulders b' b', an opening b², connecting 60 said chamber with the mouth of said draw-

head, a link-support held in said chamber b, provided with a finger projected through the opening b² into the mouth of the draw-head, and a spring seated in the chamber b, adapted to normally force said support forward, said support formed with shoulders or wings d² d³, adapted to engage the shoulders b' b', substantially as and for the purpose described.

2. The combination, with the draw-head 70 and the coupling-link, of the lifting-rod G, connected at its lower end to the pin C, its upper end projected above the car and provided with projections G² G³, and the bracket or guide II, for receiving the said upper end, 75 substantially as and for the purpose described.

3. The combination, with the draw-head A, the pin, and the lifting-bar G, formed with a lateral extension g, connected to the pin, of 80 the rock-shaft I, provided with an extension I', adapted to engage the under side of the extension g, and the bracket II, adapted to guide the upper end of said bar G, substantially as and for the purpose described. 85

4. The combination, with the draw-head, the pin, the pin-lifter G, said lifter consisting of a bar connected at its lower end to the pin, its upper end provided with projections G² G³, and the guide II, of the rocking 90 lever L, pivoted to the car-body, its upper end provided with a bifurcated projection L', said projection adapted to be swung under the projection G³ to hold said bar in elevated position, substantially as and for the 95 purpose described.

5. The combination of the pin-lifter G, provided with projections G² G³ at its upper end, its lower end adapted for connection with the coupling-link C, and the rock-shaft I, journaled on the car, adapted for lateral movement in its bearings, said shaft provided with adjustable collars M, of the oscillating lever L, pivoted as shown, its lower end disposed between said collars, its upper end 105 formed with a horizontal projection L' and with a handle portion, said projection L' adapted to be swung under the projection G³ by the lateral movement of the shaft I, substantially as and for the purpose described. 110

6. The combination, with the lifting-bar G, the lever L, and the shaft I, arranged and connected as shown and described, of the clamping-bracket O, adapted to hold said shaft from accidental lateral movement, substantially as and for the purpose described. 115
